UNITED STATES PATENT OFFICE.

THOMAS ANDREWS, OF ROCKAWAY, NEW JERSEY.

TUBE-CLEANER.

No. 828,173.

Specification of Letters Patent.

Patented Aug. 7, 1906.

Application filed January 12, 1906. Serial No. 295,736.

To all whom it may concern:

Be it known that I, THOMAS ANDREWS, a citizen of the United States, and a resident of Rockaway, in the county of Morris and State 5 of New Jersey, have invented a new and Improved Tube-Cleaner, of which the following is a full, clear, and exact description.

This invention relates particularly to improvements in devices for cleaning scale or 10 the like from the interior of steam-boiler tubes, the object being to provide a tool for this purpose of the turbine type that may be operated by air, steam, or water pressure and having ports and turbine-blades so arranged 15 that the motive agent may operate with great force.

I will describe a tube-cleaner embodying my invention and then point out the novel features in the appended claims.

Reference is to be had to the accompanying drawings, forming a part of this specification, in which similar characters of reference indicate corresponding parts in all the figures.

Figure 1 is a longitudinal section of a tube-cleaner embodying my invention. Fig. 2 is 25 a section on the line $z-z$ of Fig. 1. Fig. 3 is a section on the line $y-y$ of Fig. 1, and Fig. 4 is a section on the line $z-z$ of Fig. 1.

Referring to the drawings, 1 designates the 30 head of the cleaner, which is practically in the form of a truncated cone, and this head is provided with an annular chamber 2 for receiving the motive agent, and at the inner end of the head is a chamber 3, in which the 35 turbine 4 rotates. Communication is provided between the chambers 2 and 3 by ports 5, which extend through the wall of the head; and these ports, as clearly indicated in Fig. 4, are arranged at an acute angle, so that the 40 air, steam, or water passing through the same will strike the blades of the turbine laterally.

The blades 6 are arranged on the periphery of the turbine with a spiral trend, these blades forming the side walls of buckets for receiving 45 the motive agent. The blades are formed integral with the body of the turbine 4, and preferably a steel collar 7 is shrunken onto the blades, as clearly indicated in the drawings.

Extended forward from the turbine at its 50 center and cast integral therewith is a cylinder 8 for a piston 9, and projected outward from the cylinder and also formed integral therewith and with the turbine-wheel are 55 pairs of lugs 10, and between each pair of lugs an outwardly-extended arm 11 is pivoted,

each arm carrying a cutter, here indicated as a plurality of disks 12, mounted to rotate on a steel pin 13, having screw-threaded engagement with its arm. The arms have link connections 14 with the piston, as indicated in Fig. 1. The said links have pivotal connection with lugs 15 on the arms and also have pivotal connection with lugs 16, formed on the piston.

The outer end of the head 1 is provided with a coupling member 17 for engaging with a pipe or tube, which conducts the motive agent to the head, and extended centrally through the head and secured to its front and rear walls is a hardened-steel bushing 18, having a flange 19 at its inner end, which is received partly in a depression formed in the inner end of the inner wall of the head and partly in a depression formed in the adjacent side of the turbine. This bushing is held rigidly in position by means of a nut 20 on its outer end, said nut engaging with the outer side of the outer end wall.

Extended through and rotating in the bushing 18 is a tubular shaft 21, on which the turbine 4 is mounted, and the bore of this shaft communicates with the interior of the cylinder 8. The shaft 21 is held from longitudinal movement by means of a nut 22, engaging its 80 outer end and bearing against the end of the bushing 18.

In the operation the motive agent entering the head will pass through the same, a portion of the motive agent passing through the 90 ports 5 to the buckets of the wheel, thus imparting a rapid rotary movement to said turbine. A portion of the air or other motive agent will pass through the tubular shaft 21 and by impinging against the piston 9 will 95 force the same outward, and this outward movement of the piston obviously will spread the arms 11 to cause the cutters carried thereby to engage with suitable pressure against the inner surface of the tube.

It will be noted that with a cleaner embodying my invention the outward movement of the cutters is positive, or, in other words, the outward movement does not depend upon centrifugal force, as in some other tube-cleaners. Further, in the tool herein described the parts may be readily assembled, and the several members are not liable to get out of order. The cutters will wear practically even and last for a considerable length of time. By saying that the cutters will wear practically even it is obvious that in time

several cutters in a set will be slightly tapered because of the angle of the arms carrying the cutters; but by making the cutters of a set in the manner shown several cutters of the set may be removed and transferred from one place to another.

Having thus described my invention, I claim as new and desire to secure by Letters Patent—

10. 1. A tube-cleaner comprising a head having an annular chamber for receiving a motive agent, and also having a chamber at its inner end communicating with the first-named chamber through ports arranged at an angle transverse of the head-axis, a tubular shaft extended through the head, a turbine mounted on said shaft within the inner chamber, a cylinder on the turbine, with which the tubular shaft communicates, a piston in the cylinder, tool-carrying arms mounted to swing on the turbine, and link connections between said arms and said piston.
15. 2. A tube-cleaner comprising a head having an annular chamber for receiving motive agent, and also having a chamber at its inner end communicating with the first-named chamber through annularly-disposed ports, a bushing extended centrally through the head, a tubular shaft arranged to rotate in said bushing, a turbine attached to the tu-

bular shaft within the inner tubular chamber, a cylinder on the turbine with which the tubular shaft communicates, a piston in the cylinder, arms mounted to swing on the turbine, tools carried by said arms and link connections between said arms and the piston.

3. A tube-cleaner comprising a head substantially in the form of a truncated cone, and having an annular chamber for receiving motive agent, and also having a chamber at its inner end communicating through ports with said annular chamber, a turbine mounted to rotate in the inner chamber, blades on the periphery of said turbine having a spiral trend, a collar engaging around the blades, tool-carrying arms mounted on the turbine and a pressure-actuated piston having connection with the arms.

4. A tube-cleaner comprising a head, a turbine having rotary connection with the head, a cylinder formed integrally with the turbine, and pairs of lugs also formed integral with the turbine.

In testimony whereof I have signed my name to this specification in the presence of two subscribing witnesses.

THOMAS ANDREWS.
